ROCKET LAUNCHER

Frederick C. Lindvall, Altadena, Calif., assignor
to the United States of America as represented
by the Secretary of the Navy

Application December 29, 1944, Serial No. 570,420

2 Claims. (Cl. 89—1.7)

1

This invention relates to rocket launchers and more particularly to a rocket launcher of novel construction which may be of light weight, is easily transported, may be readily installed in firing position, and is adjustable in train by a simple operation.

One object of the present invention resides in the provision of a rocket launcher which is of compact and light-weight construction so that it may be readily transported by one person even in rough or otherwise adverse terrain.

Another object of the invention is to provide a rocket launcher which may be transported in a folded condition and may be quickly unfolded and emplaced for use.

A further object is to provide a launcher of the character described which is easily adjustable during emplacement to compensate for irregularities in the level of the ground.

Still another object is to provide a rocket launcher having simple means whereby train adjustment, to correct for minor errors in original emplacement, may be made without disturbing the emplacement.

An additional object of the invention is to provide a rocket launcher of the character described which may be readily adjusted during emplacement and then locked in its adjusted position.

These and other objects of the invention may be better understood by reference to the accompanying drawings, in which

Fig. 1 is a perspective view of a rocket launcher made in accordance with the invention, showing the launcher in its emplaced position ready for firing;

Fig. 2 is a side view of the rear portion of the launcher, with parts of the track broken away;

Fig. 3 is a detailed perspective view of the rear end portion of the launcher, showing the electrical firing contacts and the slideable mounting for train adjustment;

Fig. 4 is a front view of the launcher, shown in Fig. 1;

Fig. 5 is a front view of part of the launcher, showing the hinge connections between the supporting legs and the track;

Figs. 6 and 7 are sectional views on the lines 6—6 and 7—7, respectively, in Fig. 1;

Fig. 8 is a perspective view of the launcher in its folded position ready for transport;

Fig. 9 is a rear end view of the launcher as shown in Fig. 8;

Fig. 10 is a detail section taken on line 10—10 of Fig. 1, particularly illustrating the eccentric track lock, and Fig. 11 is a detail cross section

taken on line 11—11 of Fig. 1, particularly illustrating the loose connection between one of the legs and the rocket track.

The launcher, as illustrated, is a single-track launcher having two rails which are generally L shaped in cross section. That is, each rail has a generally vertical side 11 and a generally horizontal bottom 11a extending from the lower edge of the side and at substantially right angles thereto. The rails 10 are disposed in parallel spaced relation with their bottom or horizontal portions 11a extending toward each other. At their adjacent edges the bottom walls 11a have upturned ribs or flanges 12, while the upper edges 13 of the vertical sides 11 have inturned ribs 13.

The rails 10 form a track providing a four-point support for the rocket to be launched. More particularly, as shown in Fig. 7, the two upturned ribs 12 engage and support the lower portion of the rocket A, while the inturned ribs 13 engage and support the opposite side portions of the rocket above the ribs 12. The rocket may be of any well-known construction, such as that disclosed in a copending application of C. C. Lauritsen, Serial No. 481,644, filed April 2, 1943, now Patent No. 2,464,181. As shown, the rocket A comprises an elongated bomb case, an elongated rocket motor B secured to the rear end of the bomb case, and tail fins disposed at the rear end of the motor and surrounded by tail rings C and D. The tail rings are coaxial, and the forward ring C is insulated while the rear ring D is grounded to the rocket. The tail rings are employed to make electrical contact, as will be described hereinafter.

If desired, the vertical and horizontal portions of the rails 10 may be reinforced by stiffeners 14 in the form of strips extending diagonally between the remote edge portions of the rail walls 11 and 11a. The rails are connected in parallel spaced relation by cross members 15, one of which is disposed at each end of the track. The track formed by the rails 10 is adapted to occupy a sloping position, as will be described presently.

The lower or rear cross member 15 of the track has a pair of depending ears 16 in which a cross rod 17 is journaled, the rod 17 extending transversely of the rails and projecting a substantial distance beyond each of the ears 16. The cross rod 17, in turn, is supported at the approximate apexes of substantially pyramidal formed upright side members 18 on a base plate 19 which, as shown, is substantially wider than the track and has a shape somewhat like a scoop. Holes 19a are formed in the base plate so that stakes or

pins 19b may be driven through the plate to assist in anchoring it on the ground.

It will be apparent that the cross rod 17 provides a hinge connection between the base plate 19 and the track 10-10, and that the rear end of the track is slideable laterally on the rod 17 a limited amount with respect to the base plate. Preferably, a releaseable clamping device is provided for locking the track in its adjusted position on the cross rod 17. As shown, the locking device comprises a lever 20 rotatable on the cross rod and having at its inner end an eccentric 20a (Figs. 8 and 9) adapted to be wedged between the cross rod and the adjacent cross member 15. That is, by forcing the lever 20 downwardly from the position shown in Figs. 1 and 10, the eccentric 20a is forced to its wedging position to lock the track against lateral movement on cross rod 17, and when the lever is returned to the position shown in Fig. 1, the track is released for lateral adjustment on the cross rod. Graduations 17a may be provided on the cross rod 17 so that the amount of lateral displacement of the track on the rod can be measured.

A pair of brackets 21 (Fig. 5) is mounted on the rails 10 intermediate their ends, preferably at points about two-thirds or three-fourths of the length of the rails from their lower or rear ends. The brackets 21 are mounted on a cross member 15a (Fig. 5) having a generally triangular depending portion to which the brackets are secured. A folding leg 22 is hinged to each bracket 21 by means of pins 21a. These pins may consist of end-threaded bolts (Fig. 11), the smooth parts of which ride loosely in slightly oversize holes 22a in the upper part of each leg and in the brace 23a which reinforces it. As shown particularly in Fig. 5, the brackets 21 are so mounted on cross member 15a that the axes of the hinge connections 21a between the brackets and the respective legs 22 form a V. Thus, when the legs are swung to their supporting positions on the brackets 21, they extend in diverging relation from the rails 10, as shown in Fig. 1. Since the upper ends of the legs have loose connections with the launcher track the legs will adapt themselves to the training of the track when such adjustments are made along the rod 17. If the legs were connected only to turn on their pivots and not yield laterally thereon the legs would be subjected to undesirable twists. The legs 22 are channel-shaped in cross section and are slideable within extensible legs 23, which are likewise channel-shaped in cross section. The cross portions of the legs 23, however, face in the opposite direction to the cross portions of the legs 22.

Guide strips 24 are secured to the extensible legs 23 across the open portions of their channels so as to engage the cross portions of legs 22 and retain the latter within the channels. One of the guide strips 24 of each leg 23 includes a clamp lever 25 having an eccentric 25a, whereby the legs 22 and 23 may be locked or wedged against relative longitudinal movement. At their lower ends, the extensible legs 23 are provided with foot pads 26 in the form of circular discs pivotally secured to the legs. The discs 26 may be provided with holes through which stakes may be driven and, in addition, may be provided with cleats 27 to assist in anchoring the legs on the ground.

At its lower end, the track 10-10 has a grounded contact 28 and a live contact 29. In mounting the rocket on the launcher, the rocket assembly is placed in the track 10-10 and moved

rearwardly and downwardly until the grounded tail ring D slides under and engages the grounded contact 28, in which position the insulated ring C engages the live contact 29. The rail ribs 12 and 13 are provided near their rear ends with clearance notches 31 to avoid contact between the rails and the insulated or live tail ring C when the rocket is in firing position on the launcher. The live contact 29 extends through an opening in a plate 29a connected between the rails, and is adapted to be energized by current supplied through a cable 32 leading from a remote point into a housing 33 on the bottom of the track. When the rocket is to be fired, an energizing circuit is established from a remote current source (not shown) through cable 32, live contact 29, insulated ring C, the usual ignitor (not shown) in rocket motor B, the grounded ring D, and the grounded contact 28 to the other side of the current source.

It will be apparent that the supporting legs 22 are so mounted on track 10-10 that the legs may be folded into parallel relation with the rails, as shown in Fig. 8. In this position of the launcher, the supporting legs extend along the rails 10 toward their rear ends and lie flat against the rails so that the launcher is in a compact form which may be easily transported. Also, the base plate 19 may be folded up over the top edges of the rails, as shown in Figs. 8 and 9, to make the launcher more compact. When the launcher is folded, a single strap 34, secured to one of the extensible legs 23, may be wrapped around both of the legs as well as the rails 10 and base plate 19 to hold the parts in a compact, rigid package.

The rocket launcher is emplaced by unfolding the legs and adjusting their lengths in conformity with the terrain, the legs being clamped in their adjusted positions by the clamping levers 25. The quadrant angle of the launcher is determined by use of a gunner's quadrant or similar bubble protractor, and the launcher is aimed by sighting through the rail assembly. Slight errors in aiming the launcher may be corrected by lateral adjustment of the base end of track 10-10 on cross rod 17, the track being locked in its adjusted position by clamping lever 20. It will be understood that the cross member 15a, brackets 21 and pivots 21a provide a somewhat loose connection between the legs 22 and the rails, so as to accommodate any lateral adjustment of the rear end of the track 10-10 relative to base plate 19.

With the new construction, the launcher may be made in a light-weight form weighing approximately 30 pounds and can be set up and aimed by one man in less than a minute.

I claim:

1. In a rocket launcher, a launcher track for supporting and guiding a rocket, a base plate at the rear end portion of the track, an interengaged rod and ears forming a hinge connection between the rear end portion of the track and said base plate and on the rod of which hinge connection the ears are slideable laterally to adjust the rear end of the track and so alter the train thereof, legs adjacent to the front of the track to assume standing positions for supporting the track, and hinge connections between the track and one end of each leg, the hinges being laterally loose for adaptation of the track to the legs in training.

2. A rocket launcher comprising a launcher track for supporting and guiding a rocket, a base plate, a cross rod attached to the base plate and journaled to the rear end portion of the track,

the rear end of the track being slidable laterally on the cross rod, a pair of legs hinged to the track to form with the base plate a three-point support for the track, the hinge connections between the legs and the track being loose to provide for limited lateral yielding of the legs on their connections to prevent twisting thereof and thus to accommodate lateral movement of the rear end portion of the track on the cross rod and relative to the base plate while altering the train of the track, and clamping means turnable on the rod at any position of the rear portion of the track thereon into clamping engagement with a part of the rear portion of the track for securing said track in the particular position of train.
